Robert Nose.

By *William J. Jacobs*

Attorney

UNITED STATES PATENT OFFICE.

ROBERT NOSE, OF FAIRMOUNT, INDIANA.

FODDER LOADER.

Application filed February 20, 1922. Serial No. 537,998.

To all whom it may concern:

Be it known that ROBERT NOSE, a citizen of the United States, residing at Fairmount, in the county of Grant and State of Indiana, has invented certain new and useful Improvements in Fodder Loaders, of which the following is a specification.

The present invention relates to loading machines and particularly to fodder loaders, and while the apparatus is referred to as a fodder loader, it is to be understood that it is broad enough in its application to cover a machine for handling in bundle form, material such as corn, wheat, oats, rye, etc.

One of the principal objects of this invention is the provision of a loading machine capable of being operated by hand by a single person, and so constructed that the bundles may be lifted and thrown with varying degree of force, to the end that said bundles may be arranged upon the floor of the vehicle to which the loader is attached, in a predetermined position controlled entirely by the operator. That is to say, the operator, with full knowledge of the operation of the loader, becomes skilled in the manipulation thereof so that for instance, with the maximum force necessary to load the vehicle, he can throw the first bundles toward the front of the receiving platform, and by gradually diminishing the throwing force, he can arrange the bundles alongside one another until the rear end of the receiving platform is reached.

This manner in which my apparatus functions, is due principally to a stop device which intercepts the movement of the throwing arms, bringing them to a sudden stop and whereby the bundles are catapulted forward of the vehicle upon engagement of said arms with said stop. As previously stated, a varying degree of force applied to the means for swinging said arms will result in a variation of placement of the bundles, entirely under the control of the operator.

Briefly stated, the operation is performed by an apparatus which initially lifts the bundles through an arcuate path and subsequently projects them in a path on a line substantially tangential to their arcuate lifting path to the end that they may be placed in a predetermined position on a receiving platform dependent upon the degree of force

exerted upon the mechanism, entirely under the control of the operator.

In the accompanying drawings,—

Figure 1 is a view, partly in section and partly in elevation of an ordinary farm wagon with my loading device applied thereto;

Figure 2 is a side elevation of the crank mechanism forming a part of the means for operating the throwing arms;

Figure 3 is a top plan view of the apparatus shown in Figure 1;

Figure 4 is a rear elevation of the apparatus shown in Figure 1; and

Figure 5 is a top plan view of one form of operating handle.

In the drawings, I have illustrated a vehicle with which my invention may be associated, this consisting of a farm wagon of the ordinary type in general construction, and comprising a body frame having longitudinal side sills 2 and transverse members 4, suitably mounted on a running gear 6 including ground wheels 8. The loading or throwing mechanism comprises a frame embodying a transverse shaft 10 which is journaled adjacent its ends in bearing boxes 12 secured to the undersides of the side sills midway their length by bolts 14. Rigidly secured to the transverse shaft 10 are a plurality of rearwardly extending parallel spaced spring arms 15, the rear ends of which extend beyond the rear of the vehicle and are curved upwardly as at 16 to provide a support for the bundles during the period in which they are being lifted, this curvature of the arms preventing the bundles being thrown outwardly therefrom by centrifugal force, prior to their being thrown.

The lateral arms 15 may be formed integral with the transverse shaft 10 as shown in Figure 3 while the intermediate arms may be attached by T-couplings 18.

The intermediate portion of the shaft 10 may be provided with a crank 19 to which is connected by a bearing 20, a pitman rod 22, the opposite end of which is pivoted at 24 to an operative lever 26 pivoted at 28 in a recess 30 near the forward end of one of the side sills 2.

To the end that the lever 26 may not extend when unused beyond the side of the vehicle to an extent where it forms an obstruction during transportation, I provide said lever with a removable handle 32 as

shown by dotted lines 34 in Figure 1, or as shown in Figure 5, the handle may be hinged at 36 to the lever so that it may be folded inwardly, a latch 38 here being employed 5 to maintain the handle in unfolded or operating position.

In their load or bundle receiving position, preliminary to the lifting and throwing operations, the arms, which at this period 10 are substantially parallel with the longitudinal sills, rest upon a transverse supporting bar 40 attached to said sills adjacent their rear ends.

For the purpose of causing the bundles carried by the lifting and throwing arms, to be projected therefrom in a path substantially tangential to their arc of travel, prior to being projected or thrown, I provide a stop device which comprises a transverse horizontal bar 42 secured at its opposite end to inclined supporting stakes 44 set in recesses in the upper edges of said side sills 2, said stakes being further supported by rigid arcuate track bars 46 secured respectively at their ends to the top of the stakes 44 and the rear face of the said sills.

In operation, reference being had to Figure 1, which shows diagrammatically the principle upon which my apparatus is designed to operate, a bundle A of wheat, corn, straw or other material is placed upon the outer curved ends 16 of the throwing arms 15. The handle 32 is then manually moved in the direction indicated by the arrows, Figures 1 and 3, which through the intermediate connecting crank and pitman mechanism, will cause the entire frame embodying said arms 15 to swing on the axis of shaft 10 into the position shown by dotted lines Figure 1, at which time the intermediate portion of the spring arms 15 engage the transverse stop 42 causing their forward movement to be halted and causing the bundles to be hurled or thrown in a line tangential to their arcuate lifting path.

In the dotted line diagram shown in Figure 1, the line B—B indicates the arc through which the bundles A travel during 50 the lifting operation and X—Y the path

taken by the bundles when projected from the lifting or throwing arms after engagement of the latter with the stop 42.

From experience it can readily be seen that an operator may throw the bundles with a degree of force such that he may place 60 them in a predetermined position upon the receiving platform or rack. At the forward end of each side sill, vertical stakes or stanchions 48 are set which receive the bundles preliminarily thrown and which serve 65 to maintain the bundles piled on the rack.

Having thus fully described the construction and mode of operation of my invention, what I claim as new and desire to protect by Letters Patent is:—

1. In a bundle loading apparatus, in combination with a receiving rack, a frame pivoted thereon and comprising a plurality of spaced arms, said arms being provided at their free ends with bundle receiving portions, means for swinging said frame on its pivot to initially carry said bundles through an arcuate lifting path, a transverse stop device supported on and above said receiving rack intermediate the ends of said frame, 75 and arcuate tracks supported by said receiving rack and intermediate the ends of said pivoted frame and adapted to guide said bundles through their arcuate lifting path, said frame being adapted to be abruptly stopped by said transverse stop device to project the bundles in a line tangential to their arcuate lifting path.

2. In a bundle loading apparatus, in combination with a receiving rack, a frame pivoted transversely thereon, said frame including a crank shaft, a plurality of arms carried thereby and arranged in spaced relation with one another, the free ends of said arms being curved upwardly to provide bundle receiving portions, a pitman connected at one end to the crank portion of said crank shaft, an actuating lever pivotally supported on said rack and connected to the opposite end of said pitman, and means on said rack for 90 limiting the swinging movement of said frame thereon.

In testimony whereof I affix my signature.

ROBERT NOSE
